UNITED STATES PATENT OFFICE

167,832

FIRE FIGHTING VEHICLE

Edgar J. Graef, Dayton, Ohio, assignor to The
Duro Company, Dayton, Ohio, a corporation of
Ohio

Application January 28, 1950, Serial No. 7,556

Term of patent 7 years

(Cl. D14—3)

To all whom it may concern:

Be it known that I, Edgar J. Graef, a citizen of the United States, residing at Dayton, in the county of Montgomery and State of Ohio, have invented a new, original, and ornamental Design for a Fire Fighting Vehicle, of which the following is a specification, reference being had to the accompanying drawing, forming a part thereof, wherein:

Figure 1 is a perspective view of a fire fighting vehicle showing my new design with the top closed;

Figure 2 is a view similar to Figure 1 but with the top open to allow access to the contained apparatus;

Figure 3 represents a side elevational view of the vehicle;

Figure 4 is a front end view; and

Figure 5 is a view taken from the rear.

I claim:

The ornamental design for a fire fighting vehicle, substantially as shown.

EDGAR J. GRAEF.
